ENGLAND J. BARKER, OF CHICAGO, ILLINOIS.

EXTRACTOR MECHANISM FOR AUTOGRAPHIC REGISTERS.

1,282,039.

Specification of Letters Patent. Patented Oct. 29, 1918.

Application filed May 25, 1916. Serial No. 99,732.

To all whom it may concern:

Be it known that I, ENGLAND J. BARKER, a citizen of the United States, residing at Chicago, in the county of Cook and State 5 of Illinois, have invented new and useful Improvements in Extractor Mechanism for Autographic Registers, of which the following is a full, clear, and exact description.

My invention relates to autographic registers from which paper strips having a longitudinal series of aligned equi-distant perforations or filing holes, are, after having been written upon, extracted and torn off, and relates more particularly to the type of registers illustrated and described in my application for Letters Patent of the United States, filed March 27, 1916, Serial No. 86,867.

The object of my invention is to provide 20 an extracting mechanism which includes a reciprocable carrier having rigid pins mounted thereon, and a spring mounted channel through which the strips of paper pass, and which impales the said strips upon 25 said pins when the filing holes of the strips come beneath and in register with the pins as said strips are being extracted from the mechanism; the channel drawing said strips off of the pins when said carrier is at the 30 limit of its extracting movement. These and other objects I accomplish by the means hereinafter fully described, and as particularly pointed out in the claims.

In the drawings:

Figure 1 is an end elevation of the upper portion of an autographic register embodying my invention.

Fig. 2 is a longitudinal vertical section of the broken away end of the upper portion 0 of said register taken on dotted line 2—2, Fig. 1.

Fig. 3 is a similar view in which a longer stretch of the platen of the register is shown, taken on dotted line 3—3, Fig. 1.

Fig. 4 is a similar view taken on dotted line 4—4, Fig. 1.

Fig. 5 is also a similar view taken on dotted line 5—5, Fig. 1.

Fig. 6 is a plan view of the underside of 50 the platen showing the side-frames of the register in section in about the plane of dotted line 6—6, Fig. 2.

Referring to the drawings, A represents the side-frames of the upper section of an 55 autographic register; B the horizontally

disposed platen the side edges of which are secured to and connect the side-frames near their upper horizontal edges, and C the usual cover, which, in view of the fact that my improvements do not affect the same, is 60 not thoroughly illustrated in said drawings.

The discharge end of the platen is fore-shortened and terminates a suitable distance back of the forwardmost portion of the vertically disposed edges of the ends of the 65 side-frames, and between the transverse vertical plane of the forward transverse end edge of the platen and the transverse vertical plane of the forwardmost part of said side-frames a transversely disposed flat horizontal plate or tray D is placed, whose horizontal surface is slightly below that of said platen. The ends of tray D have blocks a, 70 a, securely mounted thereon which support the ends of the tearing-blade E, which latter 75 consists of a flat plate that bridges across the rear portion of the tray from side-frame to side-frame, and has its forward edge inclined downward at a suitable angle, substantially as shown in Fig. 2 of the drawings. 80

On either side of its center of length the tearing-blade has rigid pins G depending therefrom that terminate about half-way between said blade and tray D, and, preferably, have their extremities rounded, as 85 shown. These pins G are adapted to extend down through openings in the upper and lower horizontal plates b and c of a floating channel, which plates are arranged between the tearing-blade and the tray and 90 extend from near one block a to the opposite block a and have their ends separated by suitable inserts. The paper strips pass longitudinally over the platen and under a cross-bar 7 arranged in a superposed position over the forward end of the same, and the ends of this cross-bar 7 are made thicker and depend down and rest upon and are secured to the upper edges of side-frames A, 95 A. After the strips have been passed under cross-bar 7 they are passed between the plates of the floating channel, and from thence pass out under and in front of the tearing edge of the tearing-blade. The floating channel is secured to and supported 100 by short vertically disposed tubes 8 into the upper ends of which the extremities of pins G enter when the floating channel is at the limit of its upward movement. Tubes 8 have their lower screw-threaded ends re- 110

duced in diameter and passed through corresponding openings in the forward ends of longitudinally disposed leaf-springs 9, and nuts 10 are screwed onto said threaded 5 ends to secure the tubes to said springs.

The rear ends of springs 9 extend back under the platen a suitable distance and are secured to the longitudinal members 12, 12 of a U-shaped reciprocable frame that are 10 held against the underside of the platen by screws 13, 13, (located near the forward edge of the platen), and by screws 14, 14 (located near the rear ends of said members), which pass through longitudinally elongated slots 15 15 and 16, respectively, which limit the throw of said reciprocable frame. The forward ends of said members 12 extend beyond the forward end edge of the platen and are bent downward slightly, and tray D is secured to 20 and supported upon these forward ends, and both said tray and said ends of members 12 are provided with openings up through which tubes 8 freely pass. Immediately in front of screws 14, 14, members 12, 12, are 25 connected by a tie-strip 17 and the reciprocable frame of which it forms a part is kept at the limit of its rearward movement by means of a coil contraction spring 18, the ends of which are, respectively, connected to 30 tie-strip 17 and to the underside of the platen by suitable screws, substantially as shown in Fig. 6 of the drawings.

The forward ends of members 12 of the reciprocable frame have the upper horizontal 35 portions of inverted L-shaped arms 19, 19, secured thereto by screws or otherwise, and the vertical portions of these arms depend below the plane of leaf-springs 9 a suitable distance, and are adapted to be engaged by 40 the extremities of sickle-shaped rocking-arms 20, or by anti-friction wheels 21 journaled therein. Arms 20 are securely mounted upon a transverse rock-shaft 22, which is journaled in side-frames A, A, and has one 45 end extended through its bearings and provided with a crank 23 with which to rock it, and between the boss of this crank and the adjacent side-frame shaft 22 has a coil-spring 24 surrounding the same, one end 50 of which is secured to said side-frame and the other end to said shaft in any suitable manner. The rocking movement of shaft 22 is limited by means of an L-shaped arm 25 securely mounted thereon mediate its end 55 at its angle near the bearings of said shaft in the side-frame opposite the crank. The lower branch of arm 25 is adapted to engage the lower end of a segment shaped flange 26 projecting from the last-mentioned side-frame when tray D is at the limit of its rearward movement, and the extremity of the upper vertically disposed branch of said arm 25 is adapted to engage the rear surface of said flange 26 when the tray is at the limit 60 65 of its forward movement.

When crank 23 is turned rock-shaft 22 is turned sufficiently to cause arms 20 to engage arms 19 and push the tray forward to the limit of its forward movement and when the crank is then released, spring 24 on said 70 shaft 22 and spring 18, hereinbefore referred to, will return the tray to the rearward limit of its movement. When it does this, it is necessary for pins G, which have been previously passed through the filing-holes in said 75 paper strips, to have said strips released therefrom, to prevent said strips from being buckled and carried to the rear with said tray. This I accomplish by means of a longitudinally reciprocable wedge 27 the upper flat side of which is held in sliding engagement with the underside of the platen by means of a screw 28 which extends down through a longitudinally elongated slot 29 in the rearward extension 30 of the wedge. 80 The forward end of wedge 27 terminates (when at the limit of its rearward movement) a short distance to the rear of the forward end edge of the platen. A short distance back of this forward end the underside 90 of the wedge is beveled or inclined downward and rearward and overlaps the rear edge of a transverse bridge 31 the ends of which latter overlie and are slidable upon leaf-springs 9. A short distance to the rear 95 of this beveled surface the wedge is provided with a depending lug 32 which enters the bifurcated upper end of an arm 33 which extends from a boss that is loosely mounted upon the center of length of shaft 22 and 100 has a downward extension or finger grasp 34 depending therefrom. One side edge of the boss of arm 33 is provided with a segmental depression or recess 35, and shaft 22 is provided with a pin 36 that projects into this 105 recess 35 and is normally kept in engagement therewith by a coil expansion-spring 37 interposed between said boss and a sleeve 38 secured on said shaft. If desired, bridge 31 110 may have the forward ends of segmental leaf-springs 39 (whose rear ends are secured to the underside of the platen) bear down upon the same. When shaft 22 is turned to move the tray forward it moves independently of arm 33 until pin 36 comes in contact with 115 the lower terminus of recess 35, or in contact with the end of a gage-screw 40 tapped through the lower portion of the boss of said arm, whereupon arm 33 is rocked and propels wedge 27 forward and moves bridge 31 120 and leaf-springs 9 downward, and the latter move tubes 8 and plates b and c of the channel downward, and by the time the tray reaches the limit of its forward movement the plate c' strips the paper from pins G, 125 and when this happens and the operator releases the pressure on crank 23 the tray immediately returns to the limit of its rearward movement, and when pin 36 engages the upper terminus of recess 35 wedge 27 is moved 130

rearwardly to the limit of its rearward movement.

It will be noticed that, owing to the manner in which arm 33 is actuated, the rearward movement of the wedge is delayed and thus keeps the channel in a position below pins G until after said pins have moved to the rear of the filing openings of the paper strips from which they have been last withdrawn. In order to prevent the strips of paper from moving backward when thus released from pins G, and during the time the tray is moving rearwardly, a suitable rectangular tension-plate 41 is employed whose upper horizontal edge extends up through a recess in the forward edge of the platen and presses the paper toward cross-bar 7. The lower edge of this tension-plate is provided with a knuckle that is loosely mounted upon a transverse stationary shaft 43 whose ends are secured in the side-frames, and the upper edge of said plate is kept pressing against the paper in the manner just stated, by a spring 44 whose central yoke bears rearwardly against the plate and whose coiled ends are wound about said shaft 43.

The continuous paper strips used in conjunction with my improved register have a longitudinally arranged series of equi-distant perforations that are separated a distance corresponding to the length of the record or form printed thereon, which latter determines the length of strip which is to be withdrawn. My improvements are adapted to engage these perforations one at a time and to advance the strip just far enough to enable the operator to grasp the advance edge of the strip and then release it, leaving it to the operator to pull the strip out of the machine a distance corresponding to the full length of the record or form, and to bring the next perforation in vertical register with the extracting pins. There are usually two of these series of perforations in the paper strips, one near each side edge thereof, and when the operator desires to extract the strip he grasps the handle of crank 23 and turns rock-shaft 22, and arm 20 projecting therefrom engages arm 19 and moves the reciprocable frame forward. The tubes 8 will have pushed the floating-channel upward so that pins G will have passed through the perforations of the strips before the forward movement of said frame commences, therefore as said frame moves forward, the pins that are mounted thereon, draw the strip forward a distance corresponding to the sweep of arm 20. When the paper strips reach this advanced point, wedge 27 will have depressed springs 9, 9, through the medium of bridge 31, and tubes 8 will move downward with these springs and the floating channel will strip the paper off of the pins, and the tray and conjunctive devices will return back to their original positions. When the paper

strip has been withdrawn until the next perforations are in position to be engaged by pins G the machine will be ready for the next extracting movement.

It may happen that the operator having turned crank 23 to partially advance the paper strips in the machine, suddenly notes that a correction or addition must be made in the matter he has written. This makes it necessary to hold the U-shaped reciprocable frame in an advanced position against the pull of springs 18 and 24. For this purpose I provide a C-shaped pawl 46 fulcrumed mediate its ends to the underside of the platen at a point back of the rearward extension 30 of the wedge when the wedge is retracted. One end of this pawl is pointed and adapted to engage teeth 47 formed in the adjacent longitudinal edge of the nearest member 12 of the frame, this end of the pawl being slightly longer than the distance from its pivot to the teeth and extending forwardly of the pivot thereby holding the frame against retraction. Pawl 46 is constantly, but lightly, urged toward teeth 47 by an attenuated spring 48 which extends rearwardly from its opposite end into contact with the set-screw which secures the rear end of spring 18 to the platen. In the advancement of the frame the pawl will ride over teeth 47 successively and will hold the frame at any desired partially advanced position when the operator stops turning crank 23. But to prevent engagement between teeth 47 and the pointed end of the pawl during ordinary operation of the machine, I form the opposite end of the pawl with an outwardly turned finger which rides upon the inwardly exposed surface of a cam 45 projecting rearwardly from extension 30 of the wedge. From its root in extension 30 the inner face of cam 45 parallels the toothed edge of member 12 for a distance somewhat less than the full path of movement of the wedge. But at its tip the cam diverges sharply from the member 12. This divergence is sufficient to draw the pointed end of the pawl a considerable distance away from the toothed edge of member 12 when the rotation of crank 23 has fully advanced the frame and wedge. With the parts in this position the operator removes his hand from crank 23 and the combined pull of springs 18 and 24 jerks the frame and wedge back to retracted position before the light pressure of spring 48 can bring the pointed end of the pawl back to teeth 47. In other words, the finger on the pawl jumps from the tip of the cam to the root causing the pointed end of the pawl to skip by all the teeth 47 and seat itself in advance of the forward tooth, as shown in Fig. 6.

A plurality of superposed strips of paper are customarily used in machines of this

character, each strip having perforations for engagement by posts G. A careless operator will occasionally draw the lowest strip ahead of the upper ones, so that the perforations of the lowest one move ahead of the perforations in the upper ones. This causes the webs of the upper strips to overlie the perforations of the lowest one and necessitates advancing the upper strips upon the lowest one to bring all the perforations in register with each other and the posts. To so advance the upper strips, when the frame is in retracted position, requires separation of tubes 8 and posts G, as the strips are bound with the pressure of springs 9 between the tubes and posts—the offset relation of the perforations causing the superposed strips to present an imperforate web to the posts. It is necessary, therefore, to lower the forward ends of springs 9 and posts 8 carried thereby, and for this purpose arm 33 is provided with a handle 34 and slidably mounted on shaft 22, so that it can move to the left—viewing Fig. 1—sufficiently to clear pin 36 from recess 35 and permit the arm to be rotated forwardly from the position shown in Figs. 1 and 5, the expansion spring 37 yielding horizontally to permit this movement. To facilitate such action of the parts the shoulder of metal formed at the upper forward end of recess 35 is rounded as shown, in outline in front elevation, in Fig. 1, and, by shading in side elevation, in Fig. 5, and handle 34 is twisted slightly to present its broad surface conveniently to the left thumb of the operator. This forward movement of arm 33 carries wedge 27 forward independently of shaft 22 and the reciprocable frame—which are at rest in retracted position—and hence results in freeing the strips of paper by lowering tubes 8 through the medium of bridge 31 and springs 9. The several strips may now be shifted relatively to bring their perforations in register. Should it happen that the apertures, when brought into register with each other, stand somewhat forward of posts G, the operator will not wish to buckle the strips by attempting to push them backward in the machine until the aligned apertures shall register below the posts. Instead he can advance the posts into vertical alinement with the apertures by slightly rotating crank 23 and as he releases the crank pawl 46 will engage one of teeth 47 to hold the frame and posts in this partially advanced position; the operator may then grasp handle 34 and retract wedge 27, thereby impaling all the strips on posts G and returning pin 36 to its normal position in recess 35. The parts will remain in this slightly advanced position leaving the strips flat on the platen, until the operator completes his writing and rotates crank 23

to advance the frame and wedge the full 65 stroke.

What I claim as new is:

1. In an autographic register, the combination with a stationary platen over which a strip of paper having a longitudinally arranged series of perforations therein passes, of a member movable in a horizontal plane away from and back toward the discharge end of said platen, rigid projections carried by and movable with said member, and means that cause said projections to move into said perforations and retain the same thereon while moving forward away from said platen, and release the paper when at the limit of said movement. 70

2. In an autographic register, the combination with a stationary platen over which a strip of paper having a longitudinally arranged series of perforations therein passes, of a member movable in a horizontal plane 85 away from and back toward the discharge end of said platen, downwardly extending rigid projections carried by and movable with said member, and means movable up and down that cause said projections to move into said perforations and retain the same thereon while moving forward away from said platen and release the paper when at the limit of said movement. 90

3. In an autographic register, the combination with a stationary platen over which a strip of paper having a longitudinally arranged series of perforations therein passes, of a member movable in a horizontal plane 100 away from and back toward the discharge end of said platen, rigid projections carried by and movable with said member, and a channel movable up and down through which said strip passes which channel has openings therein in axial alinement with said projections and means whereby said channel is adapted to move upward and cause said projections to move into said perforations when said member moves forward and move down and release said paper when 105 said member reaches the limit of its forward movement. 110

4. In an autographic register, the combination with a stationary platen over which a strip of paper having a longitudinally arranged series of perforations therein passes, of a member movable in a horizontal plane 115 away from and back toward the discharge end of said platen, rigid projections carried by and movable with said member, and a channel movable up and down and comprising two transverse separated plates through which said strip passes, means reciprocable in the direction of the length of the platen that support the channel and that move said channel upward and cause said projections to move into said perforations, and devices 120 which when said member moves forward 125

moves said channel downward and releases the paper from said projections when said member reaches the limit of its forward movement.

5. In an autographic register, the combination with a stationary platen over which a strip of paper having a longitudinally arranged series of perforations therein passes, of a carrier comprising a transversely disposed plate and a superposed tearing-blade mounted on the ends thereof which is movable in a horizontal plane away from and back toward the discharge end of said platen, rigid projections depending from said tearing-blade, a channel movable up and down and having holes in its upper plate down through which said projections extend, and means that support and move said channel upward and cause said projections to move 20 into said perforations.

6. In an autographic register, the combination with a stationary platen, a stationary transverse bar extending over the discharge end of the same, and a tension plate adapted 25 to engage said bar and prevent the rearward movement of paper strips passing under said bar, of a transversely disposed carrier reciprocable in the direction of length of the platen, rigid projections carried thereby, and 30 means adapted to cause said projections to move into said perforations and to release the same therefrom.

7. In an autographic register, the combination with a stationary platen, of a reciprocable carrier, a superposed transverse tearing-blade mounted thereon, rigid projections depending from said blade, vertically reciprocable sleeves in axial alinement with said projections between which and said blade 40 strips of paper are passed, and means for causing said sleeves to move the paper so that said projections will enter said perforations when the carrier moves forward and release the paper when the latter reaches the 45 limit of its forward movement.

8. In an autographic register, the combination with a stationary platen, of a carrier, a reciprocable frame supporting the same, a superposed transverse tearing-blade mounted 50 thereon, rigid projections depending from said blade, a channel movable up and down interposed between said carrier and blade, sleeves supporting said channel disposed in axial alinement with said projections and 55 openings in the plates of said channel, longitudinally disposed springs the rear ends of which are attached to said carrier-frame and on the forward ends of which said sleeves are mounted, and means which depress said 60 springs when the carrier reaches the limit of its forward movement.

9. In an autographic register, the combination with a stationary platen, of a transverse carrier, a reciprocable frame support-

ing said carrier and slidably retained against 65 the underside of said platen, a superposed tearing-blade the ends of which are secured to said carrier, rigid projections depending from said blade, sleeves in axial alinement with said projections, springs the rear ends 70 of which are attached to said carrier-frame and which support said sleeves on their forward ends, means for reciprocating the carrier-frame, and devices for depressing said springs as the carrier-frame approaches the 75 limit of its forward movement.

10. In an autographic register, the combination with a stationary platen, of a transverse carrier, a reciprocable frame supporting 80 said carrier and slidably retained against the underside of said platen, a superposed tearing-blade the ends of which are secured to said carrier, rigid projections depending from said blade, sleeves in axial alinement with said projections, springs the 85 rear ends of which are attached to said carrier-frame and which support said sleeves on their forward ends, means for reciprocating the carrier-frame, devices for depressing said springs as the carrier-frame 90 approaches the limit of its forward movement and mechanism that retains the carrier-frame stationary at any point between the limits of its reciprocable movement.

11. In an autographic register, the combination with a stationary platen, of a transverse carrier, a reciprocable frame supporting 95 said carrier and slidably retained against the underside of said platen, a superposed tearing-blade the ends of which 100 are secured to said carrier, rigid projections depending from said blade, sleeves in axial alinement with said projections, springs the rear ends of which are attached to said carrier-frame and which support said sleeves 105 on their forward ends, means for reciprocating the carrier-frame, devices for depressing said springs comprising a reciprocable plate held in sliding engagement against the underside of said platen and 110 having a rearward extension, and a spring actuated pawl pivoted to the underside of said platen and engaging said extension; which reciprocable plate and pawl are actuated by said means subsequent to the initial movement of the carrier-frame.

12. The combination with a stationary support over which a strip of paper is moved, of devices that are immovable vertically that engage said paper, and mechanism for reciprocating said devices horizontally from and toward said support.

13. The combination with a stationary support over which a strip of paper is moved, of devices independent of said support that are immovable vertically and engage said paper, mechanism for reciprocating said devices horizontally from and to

ward said support, and means movable simultaneously with said devices for disengaging said paper from said devices when the latter have reached the limit of their 5 movement farthest from said support.

14. The combination with a support for a strip of paper, of a reciprocable frame mounted on the support, a blade fixed on the frame and crossing the forward end of 10 the support, a post fixed to said blade and adapted to enter the paper, spaced plates arranged to receive the paper between them, supported from the frame, surrounding the post and movable longitudinally thereof, 15 and mechanism for advancing the frame from and retracting it to the support.

15. The combination with a support for a strip of paper, of a reciprocable frame mounted on the support, a blade fixed on 20 the frame and crossing the forward end of the support, a post fixed to the blade and adapted to enter the paper, spacing plates arranged to receive the paper between them, supported from the frame, surrounding the 25 post and movable longitudinally thereof, mechanism for advancing the frame from and retracting it to the support, and means actuated by said mechanism for moving said plates off of the posts when the frame 30 is farthest advanced.

16. The combination with a support for a strip of paper, of a reciprocable frame mounted on the support, a blade fixed on the frame and crossing the forward end of 35 the support, a post fixed to the blade and adapted to enter the paper, spacing plates arranged to receive the paper between them, supported from the frame, surrounding the post and movable longitudinally thereof, 40 mechanism for advancing the frame from and retracting it to the support, and means actuated by said mechanism for moving said plates outwardly of the posts when the frame is farthest advanced; said means being manually operable independently of the mechanism in any partially retracted position of the frame.

17. The combination with a support for strips of paper, of a reciprocable frame 50 mounted on the support, a post fixed on the frame and positioned to engage registering apertures in the strips, a pair of spaced apertured plates, springs supporting the plates from the frame for movement 55 onto and off of the post, said plates being adapted to carry the strips between them, the springs holding the plates normally on the post, a bridge mounted on the support and spanning the springs, a wedge mounted 60 on the support for movement against the bridge, mechanism for reciprocating the

frame, and a lost motion driving connection between the mechanism and the wedge.

18. The combination with a support for strips of paper, of a reciprocable frame 65 mounted on the support, a post fixed on the frame and positioned to engage registering apertures in the strips, a pair of spaced apertured plates, springs supporting the plates from the frame for movement 70 onto and off of the post, said plates being adapted to carry the strips between them, the said springs holding the plates normally on the post, a bridge spanning the springs, a wedge mounted on the support 75 for movement against the bridge, a frame reciprocating mechanism including a rotatable shaft, a pin projecting from the shaft, an arm connected at its outer end to the wedge and formed at its inner end into a 80 boss which slidably and rotatably embraces the shaft and is recessed on its side toward said pin to form spaced pin contacting shoulders, and a yieldable element normally holding the recessed portion of the boss 85 against said pin.

19. The combination with a support for strips of paper, of a reciprocable frame mounted on the support for advanced movement away from the frame and retraction 90 toward it, a post fixed on the frame and positioned to engage registering apertures in the strips, a pair of spaced apertured plates, springs supporting the plates from the frame for movement onto and off of 95 the post, said plates being adapted to carry the strips between them, the said springs holding the plates normally on the post, a bridge spanning the springs, a wedge mounted on the support for movement 100 against the bridge, a frame reciprocating mechanism including a rotatable shaft and a coil spring tensioned between the shaft and said support to hold the frame in retracted position, a pin projecting from said 105 shaft, an arm connected at its outer end to the wedge and formed at its inner end into a boss which slidably and rotatably embraces the shaft and is recessed on its side 110 toward said pin to form spaced pin contacting shoulders, a yieldable element normally holding the recessed portion of the boss against said pin, and means independent of said mechanism for holding the frame in partially advanced position.

In witness whereof I have hereunto set my hand this 23rd day of May, 1916.

ENGLAND J. BARKER.
